(57) **CLAIM**

The ornamental design for a track lighting lamp fixture, as shown and described.

DESCRIPTION

FIG. 1 is a right perspective view of a track lighting lamp fixture in a selected tilted position showing the new design.

FIG. 2 is a left side elevational view of the track lighting lamp fixture shown in FIG. 1, the right side elevational view being a mirror image of the left side elevational view.

FIG. 3 is a bottom elevational view of the track lighting lamp fixture shown in FIG. 1 taken along the tilted axis of the fixture.

FIG. 4 is a top plan view of the track lighting lamp fixture shown in FIG. 1 taken along the tilted axis of the fixture.

FIG. 5 is a front elevational view of the track lighting lamp fixture shown in FIG. 1 in a position substantially parallel with the horizontal plane; and,

FIG. 6 is a rear elevational view of the track lighting lamp fixture shown in FIG. 5.

Features shown in dash lines depict the environment and do not form part of the claimed design.
